GEORGE F. GANTZ, OF NEW YORK, N. Y., ASSIGNOR TO GEORGE F. GANTZ AND COMPANY, OF SAME PLACE.

Design No. 3,369, dated February 16, 1869.

DESIGN FOR A TRADE-MARK.

The Schedule referred to in these Letters Patent and making part of the same.

To all whom it may concern:

Be it known that I, GEORGE F. GANTZ, of the city, county, and State of New York, have invented a new Design for a Printed Label for Lemon-Sugar Cans or Boxes; and I do hereby declare that the following is a full, clear, and exact description of the same, reference being had to the accompanying specimen, which forms part of this specification, and in which—

Figure 1 represents that part of the label which is to cover one side of the box or can, and

Figure 2 represents that part which covers the opposite side thereof.

On that part of the label shown in fig. 1, and which represents a partially-unrolled scroll, the upper part of which is spanned by a curved band, *a*, are the words "Geo. F. Gantz & Co's.", in large concave-sided capital letters, arranged upon the curved band *a*, and the words "Sicily-Lemon-Sugar," arranged upon the lower portion of the scroll; the word "Sicily," in fancy concave-sided capital letters, arranged in a slight curve above, and the words "Lemon-Sugar," in plain capitals, arranged in a straight line below.

In the centre of the scroll are two lemons, one whole, and the other divided, which are supported upon the top of a table or stand, *b*.

The sides of the scroll are of slight ogee-form, having a plain border, *c c*, which passes up behind the curved band *a*, and are joined to inwardly-bending scrolls *c' c'* at the top of the figure.

Within the intervening space between said scrolls *c' c'* is arranged a Maltese cross, *B*.

A space, *C*, is formed below the scroll, having double lower corners, *e e*, and enclosed by a plain border, *c*, around its sides and bottom.

On that part of the label shown in fig. 2, and in which is represented an unfurled banner, surmounted

by a spread eagle, and enclosed by a fancy outer border, are the words "Gantz's Sicily-Lemon-Sugar."

The word "Gantz," in large, plain, shaded capital letters, is arranged in a straight line across the upper part of the banner, and the words "Sicily-Lemon-Sugar," in plain block-letters, are arranged within an elliptic band, *b'*, the word "Sicily" in a downwardly-curved line, within the upper part of the elliptic band, and the words "Lemon-Sugar" in an upwardly-curved line, within the lower part of the band.

Within the centre of the banner is a Maltese cross.

The banner is slightly forked and fringed at the bottom, having a circular opening, *o*, at the angle or apex of the fork, and tassels *e'* pendent from the extremities of the fringe. It is provided, except at the top, with a fancy border, *f*, of a character and configuration as represented.

The banner is suspended from a horizontal arm, *g*, of a formation as represented, and carried upon a staff, *h*, upon the top of which is perched the aforesaid spread eagle, and is furthermore ornamented with a massive cord and tassels, *j j*, passing over the back of the eagle, and hanging from the ends of the arm *g*.

The outer border *E* is of quadrangular form, and composed of different-colored lines, fancifully arranged, as represented in the accompanying specimen, and ornamented at each of its four corners with a Maltese cross.

What I claim, and desire to secure by Letters Patent, is—

The design and configuration of the label for lemon-sugar cans or boxes, herein described, and represented in the accompanying specimen.
